UNITED STATES PATENT OFFICE.

PHILIP A. MYERS, OF ASHLAND, OHIO, ASSIGNOR TO F. E. MYERS AND BROTHER, OF ASHLAND, OHIO, A COPARTNERSHIP.

HAY-CARRIER.

SPECIFICATION forming part of Letters Patent No. 795,001, dated July 18, 1905.

Application filed March 15, 1905. Serial No. 250,191.

To all whom it may concern:

Be it known that I, PHILIP A. MYERS, a citizen of the United States, residing at Ashland, in the county of Ashland and State of Ohio, have invented certain new and useful Improvements in Hay-Carriers, of which the following is a specification, reference being had therein to the accompanying drawings.

This invention relates to hay-carriers, and more particularly to that type of carrier set forth in two applications heretofore filed by me—to wit, April 7, 1904, Serial No. 202,005, and October 14, 1904, Serial No. 228,425.

The general object of the present invention is to adapt that type of carrier for operation in connection with a knocker located above the track, as is preferable in the case of what is known as a "single-rail" track, and to provide a construction whereby the carrier may be rendered reversible as to the direction of its travel from the knocker when so located.

To these and other ends my invention consists in certain novel features, which I will now proceed to describe and will then particularly point out in the claims.

In the accompanying drawings, Figure 1 is a side elevation of a carrier embodying my invention in one form, the same being shown open or unlocked. Fig. 2 is a view of the same from the opposite side. Fig. 3 is a rear elevation of the same, partly in section. Fig. 4 is a vertical section taken chiefly in a central transverse plane. Fig. 5 is a plan section taken immediately below the body of the carriage; and Fig. 6 is a detail elevation of the upper part of the structure, illustrating a modification.

In the said drawings, in which there is shown a structure embodying my invention in one form, 1 indicates the track, shown as a single-rail track, and 2 the knocker, which is located above said track and is provided with cam inclines 3, oppositely inclined, and with the stop projections 4, one at each end, in advance of the corresponding inclines 3, which latter are in duplicate on each side of the track. On this track there travels a carriage 5, supported on wheels 6, said carriage in turn supporting the frame of the carrier, which is

swiveled to the carriage in any approved manner, that shown being a well-known form in which the carriage is provided with an annular flange or track 7, embraced by a grooved annular flange 8 on the frame of the carrier.

In the present instance I have shown the frame of the carrier as constructed in substantial accordance with my prior application Serial No. 202,005, although it may be constructed in accordance with my prior application Serial No. 228,425. In the construction illustrated the frame is composed of a fixed part or member (designated as a whole by the reference-numeral 9) and a movable part, (designated as a whole by the reference-numeral 10.) The fixed part carries the fixed jaw of the rope-gripping device, (indicated at 11,) while the movable member 10 carries the movable jaw 12. The fixed jaw also carries an alining-pulley 13. The combined hoisting and traction rope 14 is connected at one of its ends to the movable member 10 by means of an arm 15, extending outward from said member at one side of the frame. Said movable member 10 is provided on the other side of the frame with a bearing-stud 16, on which is mounted the hoisting-rope-guiding pulley 17. It will thus be seen that the entire weight of the load is supported by the movable member 10. This latter member is composed of two portions swiveled together by means of a vertical pivot-bolt 18. The lower portion of yoke-like form is provided with a transverse pin 19, adapted to be engaged by the tripping-dog 20, pivotally mounted on the fixed member 9, its pivot being indicated at 21. To the dog 20 there is connected, preferably by a rigid connection, the tripping-plate 22, which is arranged in the path of the sling-pulleys, so as to be engaged by these latter when the load is fully lifted. A trip-rope 24, connected to the tripping-plate 22 and passing over a guide-pulley 25, permits the carrier to be tripped at any desired point of elevation of the load below its highest point.

The upper part of the movable member 9 (indicated by the reference-numeral 26) is provided with two upwardly-extending arms 27, which pass upward on each side of the track

1 and are provided at their upper ends with stop projections 28, lying in the path of the stop projections 4 of the knocker when the movable member is elevated. The arms 27 5 pass between guide-lugs 29 on the frame of the carriage 5, so that they always maintain the same alinement relatively to the carriage and track. The upper portion 26 of the movable member thus constitutes a swiveling 10 head for said movable member, which always remains in proper relative position with respect to the carriage, track, and knocker, while permitting the lower portion or body of the movable member to turn with the 15 frame of the carrier when the latter is reversed, said lower part being suitably guided in said frame.

The carriage 5 has mounted on it on each side of the track a lifting-lever 30, pivoted 20 to the carriage between its ends on a transverse pivot 31. One end of each lever 30 is arranged to engage with the corresponding cam inclines 3, by means of which it is adapted to be operated. I prefer to provide the 25 levers 30 with antifriction-rollers 32 at the said ends to coöperate with the cam-tracks 3. Each lever is pivotally connected at its other end to a link 33, the lower end of which is pivoted at 34 to the corresponding side of the 30 swiveling head or upper part 26 of the movable member. The connection between lever 30 and link 33 is preferably a loose connection, the pivot 35 passing through a slot 36 in the link, thereby permitting the levers and 35 links to swing past the central line when the direction of the carrier is reversed, at the same time allowing the gripping-jaws sufficient play to adapt themselves to ropes of different diameters, for it will be seen that 40 when a rope of unusually large diameter is employed the downward movement of the jaw 12 is correspondingly limited, and since the downward movement of the links 33 is determined by the downward movement of the jaw 45 12, while the pivotal axes 31 of the levers 30 are fixed relatively to these variable limits, the slotted connections between the links and levers provide means for compensating for the variations of distance just referred to.

50 The ends of the sling are connected to sling-blocks 37, which latter are mounted on the bight of the rope 14, so that the bundle will assume the position with its longitudinal axis extending in the same direction as the track, 55 since the bight of the rope is in a plane transverse with respect to the track. The parts being in the position shown in the drawings and traction being exerted on the rope 14, the carrier will move forward in the direction of 60 such traction until the projections 28 of the carrier come into contact with that one of the stop projections 4 of the knocker lying on that side of the knocker from which the carrier is to travel to deliver its load. The carrier 65 being thus held stationary, the load is hoisted

until the sling-blocks come into contact with the tripping-plate 22 unless said plate is earlier actuated through the tripping-rope 24. When said tripping-plate is moved upward by either of said means the dog 20 disengages itself 70 from the pin 19, and the movable member 10 having the full weight of the load upon it drops and grips the rope 14 between the fixed and movable gripping-jaws. This downward movement brings the stop projections 28 below the projection 3, and the carrier moves off under the traction of the rope 14 to deliver its load. After the load is discharged the carrier is returned in the usual manner by a return-rope 38, connected to the rear of the 80 frame, and when the carrier again reaches the knocker the rollers 32, coming into contact with the cam inclines 3, will, through the levers 30 and links 33, lift the movable member into the position shown in the drawings, 85 at the same time permitting the dog 20 to engage again with the pin 19 and hold the movable member in lifted position. At the same time the gripping-jaws are opened by the upward movement of the movable member and 90 the sling-blocks and rope are free to descend into position to be connected to the next load. The construction is such that ample leverage is given to effect the lifting of the movable member with a minimum of resistance to the 95 travel of the carrier. When the direction of travel of the carrier is reversed, the levers 30 are free to swing upon their pivots, so as to lie in a direction opposite to that shown in the drawings, so that the inclination of said levers always conforms to the inclination of the cam inclines with which they are coöperating. The frame of the carrier may thus be readily 100 reversed with respect to the supporting-carriage, so as to travel out in either direction 105 from the knocker without requiring any manipulation of its parts other than the mere turning around of the frame, so as to cause the gripping-jaws of the rope-lock to extend in the opposite direction.

In my prior applications hereinbefore specified the gripping-jaws are shown as arranged at right angles to a line connecting the two points of support of the hoisting-rope on the carriage-frame—to wit, the point of attachment of the end of said rope and the rear face of the pulley. This necessitates a setting over of the alining-pulley to a considerable extent and a slight turning of the frame and bundle from the desired position when the 110 load is under traction. To overcome this objection, I have devised the arrangement of these parts shown more particularly in Fig. 5, in which it will be seen that the gripping-jaws are arranged at a slight inclination to 115 the line of travel, while the hoisting-rope pulley has its bearing-stud inclined at a similar angle to the central transverse plane of the carrier-frame, thus bringing the plane of rotation of the hoisting-rope pulley into line 120 125 130

with the gripping-jaws. By reason of this construction the frame does not tend to turn relatively to the carriage when under traction, the bight of the hoisting-rope will always lie in a plane truly at right angles to the line of travel, and the bundle will be carried with its longitudinal axis in accurate alignment with the track.

It is obvious that various modifications in the details of construction may be made without departing from the principle of my invention. For instance, although the movable member of the frame has been illustrated and described as designed to operate in connection with a rope-lock of the character set forth in my prior applications hereinbefore specified it is obvious that the said movable member and the mechanism for imparting vertical movement thereto may be used in connection with other devices for the purpose. Furthermore, the invention is equally applicable to what is known as a "triple-hoist" carrier, as illustrated in my prior application, Serial No. 202,005. Although I have shown and described the cam inclines, levers, and links as arranged in duplicate on each side of the track, such duplication is not essential, although preferred, and, again, although I prefer to mount the antifriction-rollers on the levers 30, employing fixed cam inclines on the knocker to coöperate with said levers, it is obvious that this arrangement may be reversed, the roller or rollers being mounted on the knocker, and such a construction is shown in Fig. 6, in which two rollers 38 are employed on each side of the track, respectively, located near the ends of the knocker, while the levers, one of which is shown at 39, are without rollers and engage directly with the rollers on the knocker.

Various other modifications will readily suggest themselves to those skilled in the art, and I therefore do not wish to be understood as limiting myself to the precise details hereinbefore described, and shown in the accompanying drawings.

Having thus fully described my invention, what I claim as new, and desire to secure by Letters Patent, is—

50 1. In a hay-carrier, the combination, with a track, and a knocker located above the same and having stops and means for actuating the movable member, of a carriage adapted to travel on said track, a load-supporting frame having a swiveled connection with said carriage and comprising a fixed member and a movable member, and a rope-lock actuated by said movable member, said movable member comprising two parts having a swiveled connection, the lower part guided in the frame and operating the rope-lock, the upper part guided in the carriage and coöperating with the stops and actuating means of the knocker, the lower part guided in the frame and having a connection for the combined hoisting and traction rope on one side thereof and a guiding and supporting pulley for said rope on the other side thereof, whereby the bight of said rope lies in a plane transverse to the track, substantially as described.

60 2. In a hay-carrier, the combination, with a track, and a knocker located above the same and having stops and means for actuating the movable member, of a carriage adapted to travel on said track, a load-supporting frame having a swiveled connection with said carriage and comprising a fixed member and a movable member, said movable member com-

load is utilized to actuate the rope-lock, substantially as described.

2. In a hay-carrier, the combination, with a track, and a knocker located above the same and having stops and oppositely-inclined cam-surfaces, of a carriage adapted to travel on said track, a load-supporting frame having a swiveled connection with said carriage and comprising a fixed member and a vertically-movable member, and a rope-lock actuated by said vertically-movable member, said movable member comprising two parts having a swiveled connection, the lower part guided vertically in the frame and operating the rope-lock, the upper part guided vertically in the carriage and coöperating with the cams and stops of the knocker, said vertically-movable member constituting a load-supporting element, whereby the weight of the load is utilized to actuate the rope-lock, substantially as described.

3. In a hay-carrier, the combination, with a track, and a knocker located above the same and having stops and oppositely-inclined cam-surfaces, of a carriage adapted to travel on said track, a load-supporting frame having a swiveled connection with said carriage and comprising a fixed member and a vertically-movable member, and a rope-lock actuated by said vertically-movable member, said movable member comprising two parts having a swiveled connection, the lower part guided vertically in the frame and operating the rope-lock, the upper part guided vertically in the carriage and coöperating with the cams and stops of the knocker, said vertically-movable member having the load suspended therefrom, substantially as described.

4. In a hay-carrier, the combination, with a track, and a knocker located above the same and having stops and means for actuating the movable member, of a carriage adapted to travel on said track, a load-supporting frame having a swiveled connection with said carriage and comprising a fixed member and a movable member, said movable member comprising two parts having a swiveled connection, the upper part guided in the carriage and coöperating with the stops and actuating means of the knocker, the lower part guided in the frame and having a connection for the combined hoisting and traction rope on one side thereof and a guiding and supporting pulley for said rope on the other side thereof, whereby the bight of said rope lies in a plane transverse to the track, substantially as described.

5. In a hay-carrier, the combination, with a track, and a knocker located above the same and having stops and means for actuating the movable member, of a carriage adapted to travel on said track, a load-supporting frame having a swiveled connection with said carriage and comprising a fixed member and a movable member, said movable member com-

prising two parts having a swiveled connection, the lower part having the combined hoisting and traction rope supported therefrom on opposite sides of the track, so that 5 the bight of said rope lies in a plane transverse to the track, the upper part of said movable member being guided in the carriage, and coöperating with the stops of the knocker, levers pivoted on the carriage and co- 10 operating with the actuating means of the knocker and links pivotally connecting said levers and the upper part of the movable member, substantially as described.

6. In a hay-carrier, the combination, with 15 a track, and a knocker located above the same and having stops and means for actuating the movable member, of a carriage adapted to travel on said track, a load-supporting frame connected with said carriage and comprising 20 a fixed member and a movable member, from which latter the load is supported, and a rope-lock actuated by said movable member, said movable member coöperating with the stops and actuating means of the knocker, substantially as described.

7. In a hay-carrier, the combination, with 25 a track, and a knocker located above the same and having stops and oppositely-inclined cam-surfaces, of a carriage adapted to travel on 30 said track, a load-supporting frame having a swiveled connection with said carriage and comprising a fixed member and a vertically-movable member, and a rope-lock actuated by said vertically-movable member, said movable member comprising two parts having a 35 swiveled connection, the lower part guided vertically in the frame and operating the rope-lock, the upper part guided vertically in the carriage and coöperating with the cams and 40 stops of the knocker, the lower portion of said movable member having a connection for the hoisting-rope on one side thereof and a guiding and supporting pulley for said rope on the other side thereof, whereby the bight 45 of said rope hangs in a plane transverse to the line of travel and the entire weight of the load is suspended from said member to actuate the rope-lock, substantially as described.

8. In a hay-carrier, the combination, with 50 a track, and a knocker located above the same and having stops adapted to engage the movable member, of a carriage adapted to travel on said track, a load-supporting frame connected with said carriage and comprising a 55 movable member coöperating with the stop, and a rope-lock controlled thereby, a lever pivotally mounted on the carriage to swing in a plane parallel with the track, and a link connecting said lever and movable member, 60 substantially as described.

9. In a hay-carrier, the combination, with 65 a track, and a knocker located above the same and having a stop and a cam-surface, of a carriage adapted to travel on said track, a load- 70 supporting frame connected with said carriage

and comprising a vertically-movable member coöperating with the stop, and a rope-lock controlled thereby, a lever pivotally mounted on the carriage and coöperating with the cam-surface, and a link connecting said lever and vertically-movable member, substantially as described.

10. In a hay-carrier, the combination, with 75 a track, and a knocker located above the same and having stops and oppositely-inclined cam-surfaces, of a carriage adapted to travel on said track, a load-supporting frame having a swiveled connection with said carriage and comprising a fixed member and a vertically-movable member, and a rope-lock, said vertically-movable member comprising two parts having a 80 swiveled connection, the lower part guided vertically in the frame and operating the rope-lock, the upper part guided vertically in the carriage and extending above the 85 track to engage the stops, a lever pivoted on the carriage and coöperating with the cam-surfaces, and a link connecting said lever and the upper part of the vertically-movable member, substantially as described.

11. In a hay-carrier, the combination, with 90 a track, and a knocker located above the same and having stops and oppositely-inclined cam-surfaces located on each side of the track, of a carriage adapted to travel on said track, a 95 load-supporting frame having a swiveled connection with said carriage and comprising a fixed member and a vertically-movable member, and a rope-lock, said vertically-movable member comprising two parts having a 100 swiveled connection, the lower part guided vertically in the frame and operating the rope-lock, the upper part guided vertically in the carriage and extending around the track on each side thereof to engage the stops, levers pivotally mounted one on each side of the carriage and coöperating with the respective cam-surfaces, and links connecting said levers with the upper part of the vertically-movable member, substantially as described.

12. In a hay-carrier, the combination, with 105 a track, and a knocker arranged above the same and having a downwardly-directed cam-surface, of a carriage adapted to travel on said track, a load-supporting frame connected to 110 said carriage and having a vertically-movable member, and a lever pivoted on the carriage with its pivotal axis transverse to the line of travel, said lever coöperating with the cam-surface of the knocker, and a link connecting 115 said lever and the vertically-movable member, substantially as described.

13. In a hay-carrier, the combination, with 120 a track, and a knocker located above the same and having a downwardly-directed cam-surface, of a load-supporting frame connected to 125 said carriage and having a vertically-movable member, a lever pivoted between its ends on said carriage with its pivotal axis transverse to the line of travel, a roller mounted on one 130

end of said lever and coöperating with the cam-surface of the knocker, and a link pivoted to the other end of said lever and to the vertically-movable member, substantially as 5 described.

14. In a hay-carrier, the combination, with a track, and a knocker located above the same and having a downwardly-directed cam-surface, of a load-supporting frame connected to 10 said carriage and having a vertically-movable member, a lever pivoted between its ends on said carriage with its pivotal axis transverse to the line of travel, a roller mounted on one 15 end of said lever and coöperating with the cam-surface of the knocker, and a link pivoted to the other end of said lever and to the vertically-movable member, said link being longitudinally slotted to receive the pivot 20 whereby it is connected with the lever, substantially as described.

15. In a hay-carrier, the combination, with a track, and a knocker having a cam-incline, of a carriage adapted to travel on said track, a load-supporting frame connected with said 25 carriage and provided with rope-gripping jaws and a vertically-movable member controlling the same, a lever pivotally mounted on the carriage and coöperating with the cam-surface of the knocker, and a link connecting 30 said lever and vertically-movable member, said link connection providing play between the lever and member to accommodate the mechanism to ropes of different diameters, substantially as described.

35 16. In a hay-carrier, the combination, with a track, and a knocker provided with oppositely-inclined and downwardly-directed cam-surfaces, of a carriage adapted to travel on said track, a load-supporting frame having a swiveled connection with said carriage and having a vertically-movable member, a lever pivoted between its ends on said carriage with its pivotal axis transverse to the line of travel and free to swing downward in either direction from a vertical position, one end of said 40 lever coöperating with the cam-inclines of the knocker, and a link connecting the other end of said lever and the vertically-movable member, said link connection providing sufficient 45 play to permit the swinging over of the lever when the carriage is reversed, substantially as described.

17. A hay-carrier comprising a carriage, and a frame having a swiveled connection with said carriage and provided with rope-gripping 55 jaws extending from one side of the frame forward in the direction of travel of the carrier and at an inclination to the line of travel so as to bring the front ends of said jaws in the central longitudinal plane of the carrier, 60 substantially as described.

18. A hay-carrier comprising a carriage, and a frame having a swiveled connection with said carriage and provided with rope-gripping jaws extending from one side of the frame 65 forward in the direction of travel of the carrier and at an inclination to the line of travel so as to bring the front ends of said jaws in the central longitudinal plane of the carrier, 70 said jaws being provided with an alining device arranged to bear upon the side of the hoisting-rope at the front end of the jaws, substantially as described.

19. A hay-carrier comprising a carriage, and a frame having a swiveled connection with 75 said carriage and provided with rope-gripping jaws extending from one side of the frame forward in the direction of travel of the carrier and at an inclination to the line of travel so as to bring the front ends of said jaws in 80 the central longitudinal plane of the carrier, and a hoisting-rope pulley mounted on the side of the frame with its plane of rotation coincident with the meeting plane of the jaws, 85 substantially as described.

20. A hay-carrier comprising a carriage, and a frame having a swiveled connection therewith and provided with rope-gripping jaws extending forward from one side thereof in the direction of travel of the carrier and at 90 an inclination to the line of travel, an alining device located at the front end of the jaws and arranged to bear upon the side of the hoisting-rope, and a hoisting-rope pulley mounted on the frame at the rear of the jaws 95 with its plane of rotation coincident with the meeting plane of the jaws, substantially as described.

In testimony whereof I affix my signature in presence of two witnesses.

PHILIP A. MYERS.
